UNITED STATES PATENT OFFICE.

VICTOR VLADIMIROVITCH DIBOVSKY, OF NEW YORK, N. Y., ASSIGNOR TO THE TYPE-RELEASE CO., INC., OF WILMINGTON, DELAWARE, A CORPORATION OF DELAWARE.

MACHINE-GUN.

1,362,479.

Specification of Letters Patent. Patented Dec. 14, 1920.

Application filed May 25, 1918. Serial No. 236,580.

To all whom it may concern:

Be it known that I, VICTOR VLADIMIROVITCH DIBOVSKY, a Russian subject, captain of the Russian Naval General Staff, residing at New York, in the county and State of New York, and whose post-office address is 57 West 75th St., New York city, N. Y., have invented certain new and useful Improvements in Machine-Guns, of which the following is a specification.

This invention is for improvements in or relating to machine-guns and has particular reference to means for controlling the movement of the extractor.

15 In the accompanying drawings which illustrate one method of carrying out this invention as applied to a machine-gun of known type—

Figure 1 represents a sectional elevation 20 through the feed block showing the spring in position;

Fig. 2 represents a plan of the spring;

Fig. 3 is a detail view of the abutment.

Like reference letters indicate like parts 25 throughout the drawings.

The extractor EX is shown in its upper position with the lock L in the firing position and the cartridge belt A with a cartridge B in position in the jaws of the extractor.

On the lower face of the front cover C which gives access to the feed block is attached by screws *s* a leaf-spring S, initially flat, which, near its free end, bears upon 35 the edge C¹ of an abutment situated upon the cover C. The act of screwing the spring to the cover in coöperation with the edge C¹ of the abutment causes the spring to assume the curved form shown in the drawing.

40 The free end of the spring S¹ is so situated that it lies in the vertical path of the extractor EX, and is engaged by the upper face thereof when the extractor has almost reached the limit of its upward travel.

45 By the manner above described in which the spring S is mounted its end S¹ is inclined downwardly and lies below the face of the abutment so that as the extractor rises it comes in contact with the free end

50 S¹ and tends to bend the spring about the edge C¹ of the aforesaid abutment. By this means the last portion only of the upward movement of the extractor is checked by a relatively strong spring acting 55 through a small distance. Immediately the

rise of the extractor is thus checked the firing of the cartridge already in position in the gun causes the lock L to move rearwardly in known manner thereby removing the extractor from the influence of the 60 spring. There is consequently no tendency for the extractor to be driven downward by the recoil of the spring before the horns or projections thereon have become engaged by the guide rails upon which they ride in 65 known manner. When the lock returns and the extractor again rises in usual manner, the action of the spring is repeated in the manner just described.

To more effectually cushion the upward 70 movement of the extractor, and prevent danger of breakage from rapidly recurring shocks the abutment C¹ is provided on its lower face with a strip C² of fiber. This may, as shown, be held in place by a clamp- 75 ing plate C³ connected by suitable rivets to the body of the abutment.

By this arrangement a relatively yielding cushion is interposed between the spring S and the metal body C¹ of the abutment. 80 As shown the spring S comprises two superposed leaves but it will be evident that a single leaf, or more than two, may be employed as found desirable.

Having thus described the invention what 85 is claimed is:

1. In a rapid fire machine gun, the combination with a gun casing, a lock casing movable longitudinally of the gun casing, and an extractor carried by the lock casing 90 and movable transversely of the gun casing relative thereto, of means for cushioning the return transverse movement of the extractor, including a spring interposed between the extractor and gun casing. 95

2. In a rapid fire machine gun, the combination with a gun casing, a lock casing movable longitudinally of the gun casing, and an extractor carried by the lock casing and movable transversely relative thereto, 100 of means for cushioning the return transverse movement of the extractor including a leaf spring attached to the gun casing and extending into the path of the extractor. 105

3. In a rapid fire machine gun, the combination with a gun casing, a lock casing movable longitudinally of the gun casing, and an extractor carried by the lock casing and movable transversely thereof, of means for cushioning the return transverse 110

movement of the extractor including a leaf spring attached to the gun casing and having its free end interposed between an abutment depending from the casing and the upper end of the extractor.

4. In a rapid fire machine gun, the combination with a gun casing, a lock casing movable longitudinally of the gun casing, and an extractor carried by the lock casing 10 and movable transversely thereof, of an

abutment depending from the top of the gun casing in advance of the guides for the lock casing, and provided on its lower face with a yielding pad or cushion, and a leaf spring attached to the gun casing and extending between said abutment and the upper end of the extractor.

In testimony whereof I affix my signature.

VICTOR VLADIMIROVITCH DIBOVSKY.
